UNITED STATES PATENT OFFICE

163,338

COMBINED MIRROR, PICTURE FRAME, AND SHELF

Joseph Sontag, Chicago, Ill.

Application December 14, 1948, Serial No. 150,154

Term of patent 14 years

(Cl. D33—9)

To all whom it may concern:

Be it known that I, Joseph Sontag, a citizen of the United States, and a resident of Chicago, Cook County, Illinois, have invented a new, original, and ornamental Design for a Combined Mirror, Picture Frame, and Shelf, of which the following is a specification, reference being had to the accompanying drawing, forming a part thereof.

Fig. 1 is a front elevational view of a combined mirror, picture frame and shelf, showing my new design.

Fig. 2 is a back view of the same.

Fig. 3 is a top plan view of the same.

Fig. 4 is a left end elevational view of the same.

The dominant features of my design resides in the portions shown in full lines.

I claim:

The ornamental design for a combined mirror, picture frame, and shelf, substantially as shown and described.

JOSEPH SONTAG.
